UNIDIRECTIONAL WIRE GRINDER OF
THE DRAGGED WORKPIECE TYPE
AND METHOD

Louis Illmer, Cortland, N. Y.

Application December 1, 1949, Serial No. 130,459

38 Claims. (Cl. 51—71)

1

This invention pertains to novel controls and improved structural features for a heavy duty horizontal grinder to meet the needs of steel wire mills or similar heavy duty requirements. My machine is particularly adapted to efficiently handle a long coil length of initially hot rolled alloy steel rod stock for subsequent wire drawing needs and to rapidly impart a fine finish thereto of high grade quality at a relatively low processing cost.

Multiple slowly advanced abrasive tapes or the equivalent fast cutting tool agencies may herein be effectively utilized to superficially treat reelable cross-sectionally circular strand or the equivalent rod stock of relatively large diametral size that is preferably dragged through one or more grinder head means in a closed travel circuit or endless loop by the employment of my perfected reeling equipment and associated plural grinder head members. To this end, fast-cutting paper-backed abrasive roll tape may be slowly advanced toward its centralized grinder zone to ultimately become commercially devitalized and substantially spent in repeated successive pass stages through such zone in order to more completely utilize the available tape life.

Laterally pliable ferrous rod stock or the like wire forming material may be unidirectionally reel dragged in a comparatively cold state at a relatively high optimum velocity to penetratively cut such treated workpiece stepwise in successive passes, the selected workpiece travel rate alone serving to furnish the desired lengthwise stroking for penetrative grinding without producing deep cut scratch marks in order to realize a high grade ultimate finish without need of additional abrasive treatment.

A long rod or wire batch may be recurrently stored upon my solitary reel in single layer formation without allowing such endless stock to become snarled into bunched formation that may interfere with freely unwrapping the same at the herein contemplated linear cutting velocity.

Tests have established that such processing in passes when working under a prescribed moderate grit backing pressure, reliably holds the resulting longitudinal scratch marks within a minute cut depth even when using fast cutting coarse grit such as 30 mesh. The cited practice in turn is closely correlated to the ultimate surface finish attained in a single abrasive zone as expressed in micro-inches. For die drawing of wire, the rod surface should be brought into a reasonably round and smooth condition, free

2

from flats or pits in order to obviate excessive die wear and to reduce other fabricating expense in attaining a superficially finished wire product of high grade quality.

5 The present innovations are intended to supplement certain structural features shown in my prior patent application, Serial No. 791,494, as filed December 13, 1947, that issued October 9, 1951, as Patent No. 2,570,953. The object of the 10 instant contribution is to elaborate on the grinder head appurtenances, the solitary tractor reel and its stator design, also on other refinements that will hereinafter be more fully set forth.

In hot rolling tough rod stock from a billet 15 into 300 to 400 lb. batch lengths, particularly when working at reasonably high rolling mill speed with circular alloy steel stock having its tensile strength annealed to about 100,000 lbs. per sq. in., it is found difficult to uniformly hold its out of round tolerance to better than $\pm \frac{1}{64}$ ". Owing to bearing misalignment and wear, the profile of such stock may suffer from outwardly projecting fins or overfilled cusps that require special abrasive treatment to reach a truly cylindrical finish devoid of flats or slivers.

As an initial operation, it is usually preferred to straighten and initially predraft such annealed heavy duty rod stock in one or more light cut passes through the die block of a supplementary wire drawing bench to impart a more uniform profile to such defective rod stock by slightly reducing its diametral size from about $\frac{3}{8}$ " to about $\frac{31}{32}$ " gauge. The rod batch may thereupon be operatively installed onto my grinder machine reel into a welded endless loop formation and made ready for efficient further diametral reduction by tape grinding means preferably embodied in a rotary head that circumscribes a reel dragged workpiece. The linear velocity imparted to such installed one-piece batch may herein be dragged 30 at several thousand feet per minute through co-acting multiple tapes, each preferably 4" in width.

Such pressure backed, slowly fed tape is made 45 self-compensating as regards its infeed toward the workpiece in order to maintain a substantially uniform cutting quality. Annealed high carbon steel rod stock of about $\frac{3}{8}$ " in size normally requires a radial grinder cut depth of less than 0.008" to remove about eight percent of its batch weight in order to displace all decarbonized surface metal and to otherwise prepare a pitfree core metal finish. Such processing expedites wire drawing at a relatively fast drafting rate without need of further abrasive treatment to preserve

the original ground rod characteristics. The coarser the allowable tape grit, the correspondingly higher will be the attained metal removal rate per cu. in. of spent grit.

Such processing is purposely confined to a period while the rod still possesses considerable gauge size and prior to final wire drawing as kept at a small superficial area per pound of rod stock which in turn curtails stock wastage. After being drawn into wire, the surface magnitude becomes considerably augmented and hence would require more abrasive tape to effect a given reduction in batch weight. Abrasive tape may generally be considered commercially spent after about one-half of its original grit depth has been utilized for metal cutting purposes.

Rod stock rolled to larger than $\frac{3}{8}$ " gauge usually becomes increasingly difficult to crimp and readily set about a reasonably small sized reel. The rod treatment herein taught readily admits of economically fabricating alloy steel wires of $\frac{1}{2}$ " gauge. The permissible linear drag velocity for reeling such wire is somewhat restricted over smaller wire sizes but not to an abnormal extent.

It is pointed out that by the use of my unidirectional reeling system, the coil set is purposely confined to four single-acting or simultaneous one-way crimps per batch pass which in turn results in a substantial power saving over conventional reeling methods where heavy duty, fast running rod stock is concerned.

Abrasive roll tape that is linearly advanced tangentially of reeled rod stock, also affords a decided advantage in cost per sq. in. of available grit area over lap-spliced tape belts of the comparatively shorter high speed endless type. The latter are also more likely to suffer incipient tear by grit crack or the like defects when rapidly brought into a sharply crimped cutting zone disposed to embrace a reeled strand. Such disposition calls for the use of finer mesh grit at a correspondingly larger expenditure thereof to satisfy given rod grinding needs.

My tape feed controls also permit of penetratively grinding down larger sized rods and then cold drawing the same by the so-called "patented process" without rod annealing upon being hot rolled. Such process involves an increased number of workpiece passes to effect a prescribed reduction in batch weight. For most efficient fabrication, the rod stock should in any case be preground to realize a refined and uniformly sized cold drawn wire product at a relatively high drafting rate. Unannealed alloy rod stock is inherently hard to handle and requires augmented drawbench power for a given gauge size.

In addition, roll tape may be more compactly stored within rotating head confines and made to abrade a considerably greater number of successive rod batches of a fixed weight without need for frequent extended grinder shutdown for replenishment of the tape supply.

Reference is had to the accompanying seven sheets of drawings directed to such revised exemplification, and in which drawings:

Fig. 1A shows a partial top or plan view of the fore portion of my novel grinder assembly equipped with a unidirectionally driven primary reel and cooperating stator means therefor, and Fig. 1B represents the aft end view of such grinder unit.

Figs. 2A and 2B respectively depict corresponding elevational side views of Figs. 1A and 1B.

Fig. 3 is a face view of one of my rotatable grinder heads as seen from 3-3 of Fig. 1A, the face cover being removed.

Fig. 4 presents an enlarged detail of the centralized grinder zone region of Fig. 3.

Fig. 5 shows a top view of a driven head spindle assembly or unit having a chambered disc affixed to each spindle end of which one such is cross-sectionally detailed as taken along 10 5-5 of Fig. 3.

Fig. 6 reveals in enlarged scale, the slip hub details of my tape offtake bobbin; and Fig. 7 is an enlarged partial side view of Fig. 4 and which in perspective, details one of my complementary tape backing shoes.

Fig. 8 shows in partial cross-section, a rim fragment of my solitary tractor reel rim and its associated stator rings as taken along 8-8 of Fig. 1A, and

20 Fig. 9 is a reel slot bolt detail taken along 9-9 of Fig. 1A.

Referring more specifically to Figs. 1 and 2, such grinder assembly preferably comprises a smooth faced tractor reel 10 devoid of rim grooves that may be carried by a horizontal main axle 11 that spans mated bearings such as 12. Each bearing may be superimposed upon a pedestal 13 erected on base plate means such as the pair of channeled rail sections 14A and 14B that may extend in parallelism throughout the length of my grinder assembly as shown.

A primary gear type motor 15A of the inbuilt speed reduction type may comprise a gear casing 15B and have its slow speed outlet shaft coupled directly to one reel axle end. The oppositely extending special armature shaft of such motor may be equipped with an additional spur reduction gear 15C that is intended to be intermittently operated by a relatively small supplementary motor 16A shiftably mounted on the skids 16C and having a pinion 16B. The latter is adapted to selectively mesh with or be disengaged from the gear 15C. When actively combined, the last named gear operates through the reduction gears 15B of the primary motor. The shift movement imparted to said pinion may be made to roller actuate a wiper safety switch or circuit breaker 15D that cuts out current flow to the primary motor 15A during the interval the said pinion is operatively engaged. This motorized axle drive is such that my reel may be rotated at two different speeds of which the slower may be utilized to replenish a completed endless wire batch in a manner presently to be described.

55 My tractor reel assembly is preferably provided with a cast iron sleeve-like rim section 17A whose respective interiorly bored end regions are affixedly centered upon the reel axle 11 between the latter's outboard bearings by a pair of axially interspaced support pulleys 17B and 17C (see Fig. 8). One sleeve end region may comprise an exteriorly turned coil gripping length 17D preferably but not necessarily of uniform cylindrical size which is shown stepped radially inward by a shallow concentric ledge 17E. The other sleeve end may if desired terminate in a flanged conically flared enlargement 17F with respect to its contiguous neck dimension given to medial body region 17G. The exterior of such body region may be embraced by an aluminum or the like sheath 17H that affords an inherently low coefficient of friction.

A minor coil group 19A of my endless workpiece 19 may be grippingly coiled about the un-sheathed rim section 17D. Such coil group is

herein automatically thrust axially by rotation of the driven reel and over the annular ledge 17E which thereupon slackens the remaining coil tension resulting from unidirectionally dragging the treated workpiece loop through one or more abrasive zones. Most of the reel gripping coils are disposed in close lateral proximity so that a spiral shift on part of the last laid reel coil will cause all leading coils to slowly move in unison toward the remote end of the reel body. Such windings enable an exceptionally long wire to be stored as a work piece which eliminates the need for frequent replenishment of successively completed wire batches. While Fig. 8 shows my longitudinal rim profile as superficially stepped, this may be kept straight-faced, particularly as applied to a short batch length.

Referring now to the improved camming means by which said last laid coil may continuously be pushed axially, this preferably comprises a series of angularly distributed ball bearing, wire shifting rollers or the like camming means such as 20A, 20B, etc. that may respectively be collectively mounted upon stationary ring-shaped carrier or principal stator 21A and which rollers may be distributed about the entire stator perimeter. This ring may be adjustably erected upon certain of my base rails such as 14A by reversed wedge blocks 22A and 22B. Upon being firmly bolted into place, they allow the exterior of said carrier to be rigidly supported in arcuate circumscribing registry with the reel axle 11. Radial gauge rod means 23 (see Fig. 2A) may be used to align the face of the reel section 17D with the tangential pads 33 on said stator.

Such stationary roller carrier may be kept interspaced endwise from its contiguous reel end (see Fig. 8). An offset bracket arm having an individual pad flange 24 may be demountably bolted to retain each of my liftable, relatively flat antifriction rollers 20A, 20B, etc. whose respective perimeters may slightly overhang the rim section 17D as shown. Each such spring backed roller may be mounted to slidably retract upon a headed guide pin 25 to clear the reel should its rim fail to run concentrically. This series of flat rollers may be progressively advanced spirally around the entire perimeter of the principal stator 21A in the reel axis direction by suitably selected flange shims 26 that collectively compensate for the maximum expected gauge size of the prelaid reel coil windings.

When the primary reel is rotated by the motor 15A, the cited roller arrangement automatically causes the last laid reel coil to be uniformly and slowly thrust laterally whereby the previously laid reel gripping coils are successively pushed over the stepoff ledge 17E at a comparatively low shift velocity. All such coils are herein subjected to a substantially continuous rather than intermittent lateral shift movement that substantially obviates the need for setting up of a high static friction coefficient to repeatedly initiate successive coil shifts. Hence the distributed roller disposition facilitates the desired axial shift on part of my contemplated numerous reel coils at a minimum of thrust requirement. For heavy duty service, a considerable number of distributed high speed rollers are usually needed to absorb an accompanying heavy thrust without involving ball bearing overload and still be able to exert a combined thrust absorbing effort sufficient to handle $\frac{3}{8}$ " alloy rod stock as prewrapped around a tractor reel of some 6 ft. diameter by 4 ft. long.

In order to prevent an aggregate thrust of such magnitude from reaching the reel axle 11, I may further provide for a substantially identical but opposed secondary stator 21B at the other end of the tractor reel equipped with a plurality of counterbalancing thrust rollers such as 27. These non-retractile rollers may collectively bear against the remote reel face end and be separately bracketed to their stator 21B as shown.

The parallelly mounted stators 21A and 21B may further be provided with complementary ear lugs 30 having multiple stay rods 31 interbraced therebetween to constitute a laterally rigid cradle. Upon removal of the wedge blocks 22A and 22B, said cradle may be bodily rocked about its axis to manually bring a particular roller pad 33 into an accessible servicing position.

As elaborated upon in the aforesaid pending patent application, my reel perimeter is preferably given a diameter kept in a certain optimum relative to the treated wire size to allow of repeatedly imparting a limiting crimping stress without undue fatigue and still have the wire set to snugly hug the coil gripping section 17D of a fast running tractor reel of comparatively small size.

The abraded stock or workpiece 19 is preferably treated in a closed circuit or endless loop of which the abutting ends are smoothly welded together. In Figs. 1A to 2B, a reel leaving region of such loop may be carried off the bottom of the tractor reel to a pedestal mounted idler sheave 28 preferably of the skewed axle type arranged to laterally divert the returning wire into alignment with the tandem grinder heads 32A, 32B, etc., as shown.

Such sheave may be provided with one or more wire tensioning jacks 35 that bodily shift the sheave axle. It is preferred not to excessively tension the looped wire as it enters the tandem grinder heads. In order to counterclamp and rectify such entering wire as preset to the idler sheave, resort may be had to a triple roller straightener device 36 (see Fig. 1B) of which the intermediate roller position may be adjustably organized. Said straightener may be combined with a wire clamp 36A as used for workpiece replenishment purposes. The tension which the driven tractor reel normally exerts upon its oncoming wire then becomes equal to the total head drag plus an initial moderate tension imposed by the jack 35. As will be understood, the collective width of all advanced tapes is a measure of such total head drag after allowing for internal wire crimp losses.

The balanced mated or long travel-range thrust screws of my dual jacks such as 35 are respectively located upon opposite sides of the strand redirecting sheave 28 and which screw jacks are shown chain interconnected for simultaneous adjustment to self-lockingly retain the pulley axle in a maintained acute inclination to the horizontal tractor reel axle 11. It will be obvious that the worm screw drives of such jacks may likewise be simultaneously actuated by a remotely controlled electric motor of the reversible type by which to more rapidly establish any desired tensioning of the workpiece and thus accelerate the productive rate of my grinder machine.

The bottom region of the secondary stator 21B may sustain a comparatively few spirally stepped strand guide rollers as 37A, 37B, etc. serving to work the next adjacent reel coils up-grade along the frustro-conical rim section 17F prior to leav-

ing the tractor reel 10. An augmented wire tension is thereby built up that approximately conforms to that imposed by the setting of the jack adjustment. If preferred, said conical rim formation 17F may be eliminated without need of the strand guide rollers 37A, 37B, etc. by directly returning a portion of the wire loop 19 obliquely onto the bottom of the sheave 28.

The wrapped length of my reel installed wire batch may be successively treated in relatively long or short mill run lengths. A reel leaving portion of such length course may be diverted over the guide pulleys 37A, 37B, etc. for delivery from the remote end of the tractor reel as indicated in dotted outline. When used, said guide rollers may be propped conjointly with certain of the thrust rollers 27 in the fashion represented in Fig. 8.

A skeletonized stand or superstructure for mounting my grinder heads in tandem may comprise a dual set of interspaced rolled uprights of structural steel such as 38A, 38B, etc. that may rest upon sole plate rails. Each such set of uprights may serve to prop the laterally spaced horizontal stringer beam 39A or 39B of rolled channel shape.

As detailed in Figs. 3 to 5, complementary narrow bracket castings 40A and 40B may affixedly span said beams to support the pair of interspaced spindle bearings 40C and 40D. Corresponding ends of said brackets may be integrally extended upwardly into risers as shown, to carry demountable bearings for a head drive shaft 41 and a parallel tape feed shaft 42. One end of the shaft 41 may be directly connected to the gear motor 43 while the opposite ends of the shafts 41 and 42 may be suitably geared to run in unison and thus feed the tape advance at a very slow rate crosswise of the wire axis.

A comparatively short tubular head spindle 44 operatively runs in the bearings 40C and 40D and each spindle end has a similar chambered circular head 32A or 32B reversely affixed to respectively include a disc wall or web plate 45A having a circumscribing rim flange 45B. Such spindle may be geared to run from the shaft 41. Loosely mounted about said spindle intermediate each such head and an adjacent spindle bearing, is a twin spur or sun gear 46 driven from the feed shaft 42.

The open mouthed edge of the rim flange 45B may be countersunk for the centered reception of abutting semicircular closure panels of transparent sheet plastic, glass or the like pane 47 which may be demountably retained in place by multiple fasteners to seal the head chamber against dissipation into the surrounding atmosphere of waste stock and spent grit. Such closure components may each provide for a grip handle and be centrally apertured to mount a replaceable split wear bushing 48 that guidingly passes the endless workpiece 19 therethrough.

Said transparent panels permit the condition of the threaded tapes to be readily inspected while the rotating heads are intermittently shut down. When opened, accumulated entrapped surplus of ground particles may from time to time be dumped into individual storage pans 49 upheld beneath the stringer beams 39A and 39B.

Mounted within each head chamber are opposed duplex tape advancing feed rollers 50, each comprising a keyed roller shank 50A that may be overhangingly journaled through a boss fixed on the disc 45A. The bearing end of the shank 50A is provided with a driven planetary

70 75 76

head gear 50B arranged to mesh with a sun gear 46.

Between each feed roller and its disc boss, there may be interposed a narrow compensating spur gear 51 affixed to rotate with the feed roller. An intermediate idler gear 52 may mesh in registry with said compensating gear for tape takeup purposes, the hub of such idler gear being shown partially inset into a socket in the wall 10 45A. The feed roller may also be provided with a pair of end flanges such as 53 of which one may be demountably retained by a snap ring 54. The exterior of the feed roller 50 may be sheathed by a yieldable tubular sleeve 55 to 15 fortify the frictional grip of the tape trained therearound. A radially spring pressed auxiliary roller 56 acts in a like capacity.

Each feed roller cooperates with its own tape supply bobbin 57A or 57B and a corresponding 20 complementary tape offtake bobbin 58 that are all compactly installed within the confines of my chambered head. A separate roll of abrasive tape 59 is withdrawably mounted on each supply bobbin with its grit face exposed outwardly. Said mated bobbins are both pin mounted and otherwise rendered interchangeable. Such tape supply is carried over the driven feed roller sleeve and diverted by the idler or tape roller 60 to deliver tape through my centralized grinder zone 25 30 35 40 45 50 55 60 65 70 75 80 85 90 sion springs such as 65 thrust against the end of one such tube whereby by relative tube slip or overtravel, the spent tape tautly follows up as fast as it becomes released by the feed roller. Said conical slip connection further facilitates the dragging of a replacement tape through my grinder zone.

The opposite ends of the takeup bobbin 58 are preferably flanged as shown to stack its oncoming spent tape in aligned roll formation. The workpiece drag exerted upon my opposed relatively wide tapes when passing through their respective grinding zones, tends to laterally shift such tapes longitudinally of the wire axis, hence one rewound tape edge may become unduly crowded toward a contiguous bobbin flange. To correct such faulty performance, the supported end of the bobbin pin 63 may be tiltably disposed by a bolted flange 67 having a rectilinear lobe 68 that may rockably bear exteriorly against the head disc 45A to constitute retaining means for setting the tilt of said pin. Such mounting permits of adjustably inclining said pin to equalize the drag tension along both tape edges without incipient tear. The same result may be obtained by imparting a slight taper to the feed roller sleeve 55 to bring about axial tape creep toward the divergent taper end, particularly when the reel 10 is made to run unidirectionally.

The spent tape as wrapped upon the takeoff bobbin may have a metallic core bushing or the like reenforcement 69 affixedly inserted into the bore of its roll tape. A slotted core tube end may register with a dowel carried by the outer tube 62 to facilitate bobbin withdrawal. A roll of partially spent roll tape may then be readily interchanged to serve as a transferred supply bobbin. Such retrieved abrasive may still possess a considerable cutting capacity. By stocking alternate grinder heads with virgin tape and with such partially dulled tape, their combined cutting action is likely to be reduced to about three fourths but such practice cuts the virgin grit requirement to approximately one half.

Should a previous supply bobbin become substantially depleted, my rotary grinder heads may be shut down to remove an outer bobbin flange such as 58 (see Fig. 6). After snipping a tape end region, its remaining abrasive roll may be freely withdrawn endwise. By now reversing the severed roll tape ends and remounting the same in interchanged relationship with a contiguous fitted offtake bobbin, overlapping ends of each newly conjoined tape may be clipped together to establish a reversed travel path through its original grinder zone. If preferred, other sets of my duplex bobbins may likewise be interchanged, all tape rolls in accordance to my improved method being wrapped on their respective bobbins in one and the same direction. Such dual stepwise tape utilization is preferably achieved by the use of the reversing gears 52 as interposed between the driven feed roller 50 and its mated bobbin gear 64 (see Fig. 5). If desired my mode of repeated grit treatment may be extended to include more than two tape passes without having to withdraw the interposed tape from its backing jaws.

It is further expedient to presoak all supplied roll tape in a solution of oil or the like fluid in order to realize to a certain degree the enhanced cutting quality afforded by wet over dry grit grinding. A raised platform 70 may be disposed along the drive shaft side of my grinder heads

to facilitate the cited transference of spent roll tape and other servicing.

Attention is now directed to my improved duplex grinder zone as detailed in Figs. 3 to 5. Projecting beyond each end of the head spindle 5 Projecting beyond each end of the head spindle 44 is affixed a bifurcated shoe bracket. One branch thereof 71A supports a bored casing 72 containing a hollow piston 73 of which its head 5 interiorly carries a threaded stem extension and which head end is further forked to transversely mount a shoe trunnion 74. A compression spring 75 or the like agency may be installed within said casing to impose a relatively light tape backing thrust upon the treated wire.

The trunnion 74 pivotally mounts an inherently stiff shoe assembly 76 (see Fig. 7) while a similar opposed trunnion 77 is shiftably mounted by the other bracket branch 71B to carry another like shoe 78. My pair of superimposed tapes are operatively threaded between each inturned shoe face and their common workpiece to feed axially crosswise thereof.

Each opposed backing face of such shoes may be longitudinally slotted as shown to respectively have a relatively soft rubber or the like cushioning strip 79 alignedly inserted therein. The bottom of each shoe slot may be kept square in profile to cooperate with a contiguous circular rubber shape that provides a clearance space or elongated cavity 79A into which to more readily compress such wire straddling resilient strips. A thin metallic cover plate 80 may span each mouth of such shoe slot and underlie the tape thereof to mitigate rubber wear.

My illustrative shoe arrangement is more particularly adapted to handle wires in excess of $\frac{1}{8}$ " diameter. Associated with the trunnion 77 is an offset stop flange 81 that confines in registry each pair of superimposed tapes against abnormal edgewise shift by workpiece drag.

In addition, each opposed inner shoe face may be provided with an elongated mouth protuberance 82 to extend alongside and beyond the mated edge of its strip receiving slot to further increase the wrap of relatively pliable tape as fed into the centralized abrasive zone 83. The concaved face disposition in turn correspondingly augments the cutting capacity of each grinder head in a proportionate relation to the effective contact area that can be established between the coarse tape grit of a prescribed width and relatively small sized rod stock to rapidly and penetratively abrade the same at the minimum of grinder attendance cost.

At the other edge of my strip receiving slot, an apertured shoe sideface lug 85 may be provided to mount a fulcrum rod 86 therethrough that carries a tape guiding roller 87 at the respective rod ends. Such refinement serves to smoothly maintain the feed of a relatively wide abrasive tape against lateral distortion when laboriously dragged toward its feed roller 50.

For treating wire of substantially different diametrical sizes, it is preferred to accurately adjust the centralized interspacing between my centralized interspacing between my opposed shoe faces from the exterior of a closed grinder head. A slidably abutment rod 88 may reach radially through each head rim 45B and the bracket branch 71B to shiftably adjust and fix the shoe trunnion 77 at the inner rod tip. The outer rod end may be provided with an interposed thrust spring 89 that may be set up by the lock nut 90 to keep the dragged work piece 19 centralized with respect to its circular head.

11

The other trunnion 74 may be subject to a selective degree of counterthrust by means of a radially insertable reach rod 91. To this end, the spring casing 72 may have a socket-headed screw bolt 92 entered through its casing cover for engagement with the threaded stem extension of the piston 73. Said bolt may be equipped with a demountable coupling 91A whereby to adjustably accommodate the tension of the spring 75 to the needs of different sized treated workpieces without opening the head panels 47.

As a simplified alternative mode of tape feed manipulation, next adjacent bobbins of one of my tapes (see Fig. 3), after having been transferably fed off a trailing bobbin to substantially fill a mated leading bobbin, the motorized tape feed may be manually or automatically timed to periodically interrupt such feed by shutting down the drive motor 43.

During such period, any one of the tapes may be momentarily slackened lengthwise to permit an operative interchange of their mated bobbins about their respective hub pins 6 and thereby effect a spliceless tape feed reversal without having to sever either tape end region. It will be obvious that virgin grit will cut faster than a partially spent abrasive, the relative cutting rate being dependent upon the grit mesh and the degree of its prior grit loading or wear. Where successive rod stock batches are held reasonably uniform in gauge size, the abutment rod 88 and its reach rod 91 may be dispensed with.

By applying suitable timing switch means to the tape feed motor 43, I may collectively shut down or reverse the feed direction of certain roll tapes when closely approaching one of their respective ends. Subsequent to such shutdown period, my unidirectional reel preferably continues to linearly advance its endless workpiece without travel reversal or need for installing a new partially ground batch of bundled coils in order to effect the completed multistage grinding thereof. Furthermore, by virtue of my refined abrasive treatment, the repeatedly passed endless workpiece may be ground to any desired diametral size throughout such batch length without forfeiture of any considerable rod end stock.

It now remains to describe the manner in which to successively replenish workpiece batches of diverse mill run lengths without appreciable loss in wire stock. When the grinding of a relatively long batch indicated in Fig. 1A, has been completed and it is desired to follow up with a relatively shorter batch, then certain surplus coils contained in the prior batch may to advantage be removed from the tractor reel 10. The present grinder is designed to drag a renewal batch into operative position at the trailing end of a preceding batch in a one-way reeling direction without reversal.

For such practice, a batch supply drum 94 and a batch takeoff or bundling drum 95 may in close association be interposed between the first entered grinder head 32F and the idler sheave 28 (see Fig. 2B). The last named drum may be mounted upon a driven shaft 96 superimposed crosswise of one stringer beam such as 39B and which shaft is controllably rotated by an auxiliary motor 97 (see Fig. 1B).

As a further feature, the reel 10 may be provided with a plurality of parallelly distributed T-slots such as 98 of which one is transversely detailed in Fig. 9. By virtue thereof, a particular loosely wrapped coil embracing these undercut

5

slots, may be secured into a special headed T-bolt 99. A contiguous coil may then be raised by a suitable pry tool (not shown) into a relatively elevated position 19' where it may be conveniently severed by sawing or the like manner.

First assuming an initially installed batch to be longer than the next reel oncoming batch, such shorter replenishing batch may as a bundle be initially placed around the supply drum 94. After severing the original loop splice of the prior batch by use of the clamp 36A or the like, one wire terminal may be attached to the outer end of the supply bundle and its other terminal region threaded through the precasting or crimper device 100 kept substantially identical to the wire straightener 36, and thence attached to the driven drum 95.

By now starting the auxiliary motor 97, the leading end of an unclamped renewal batch may be slowly dragged onwardly until its original splice to the prior batch reaches a medial position on the reel 10. The T-bolt 99 may now be put into place to allow the liberated surplus wound coils of said prior long batch to be circumferentially stripped off the reel 10. While said reel is blocked against rotation, the motor 97 may in this fashion withdraw sufficient coils to permit their receding loose ends to be directly respliced to said reel clamped wire end. Thereupon by release of the clamp bolt 99, a further running of the motor 97 serves to bundle the remainder of such long batch onto the offtake drum 95.

When these respliced wire ends reach a location intermediate the drums 94 and 95, such weld may be severed to permit of bodily removal of the now wholly bundled prior batch. A final welding together of both terminals of the renewal batch completes the installation of a shorter batch loop made ready for grinding when retensioned by the sheave jack 35.

On the other hand, in the event the aforesaid shorter batch should be followed by a comparatively long replenishing batch, the supplementary motor 16A may be placed into operation (in lieu thereof the regular main drive motor 15A may be successively inched over) to build up additional coils on the reel 10 by bringing the original loop splice onto a medial portion of the reel where it may be severed. By slidably clamping one wire terminal to the reel by the bolt 99 while the mated wire terminal is allowed to spring loose from said reel, additional coils may be built up to augment the reel coils. Should said supplementary motor 16A now be started up, this will draw wire from the supply drum without delivery to the takeoff drum until a measured number of further coils are incorporated to correspond to a desired longer replenishing batch. The trailing end of the prior loop may thereupon be coupled to the leading end of such longer batch. The operation of the motor 97 will then cause all of the initially ground short batch to be bundled upon the offtake drum and at the same time carry such coupled wire region into the vicinity of both drums. Finally, by disengaging said coupled wire ends and welding the longer renewal batch into a loop, it too will be made ready for abrasive treatment. It will be noted that all my finished batches are devoid of any intermediate splice connections between the ends of their finally finished and bundled length.

When reeling a comparatively short endless rod batch, it is preferred to increasingly incline the lateral approach of the reel leaving coil to-

12

ward the offtake roller 37A (see Fig. 1A) and thus eliminate the need for the reel slots detailed in Fig. 9.

By virtue of the relatively wide duplex roll tape afforded by each grinder head, these may be reduced to two or three rotary head pairs and with coarse grit tape still attain a fast grinder output designed to materially cut present-day attendance cost per ton of product. The fact that slowly fed 30 grid paper-backed tape may readily be utilized in multistages, also serves to reduce tape grit costs for refining heavy steel rods to as low as \$10.00 per ton of product.

In addition, the first cost of my grinder unit is kept reasonably low by the abundant use of standardized or the like catalogued machine parts; the power requirements are likewise confined within proper bounds by adequate reduction in coil crimp losses. In certain instances, a single attendant may serve more than one grinder unit.

It is believed that the foregoing rather explicit structural disclosures and their functional behavior, will make evident to those skilled in this art, the more outstanding commercial and operative advantage afforded by my grinder improvements, and I reserve the right to equivalently modify such illustrative design features, all without departing from the spirit and scope of my invention heretofore described and more particularly characterized in the appended claims, it being apparent that the accompanying multistage grit cost for rod grinding may be made to drop significantly per ton of performance. Should a lesser than 8% weight reduction be required or the treatment of relatively softer metallic stock be involved, such light duty processing may materially lower corresponding grit costs.

I claim:

1. A strand processing machine comprising a driven tractor reel including a rim adapted to have a group of strand coils spirally trained thereon, cutting tool means arranged to superficially treat a reel oncoming strand portion as a workpiece, separate stator means respectively located adjacent to each rim end, stator sustained roller means reversely assembled upon each such stator means, one of the roller means serving to laterally thrust the last laid rim coil axially of said reel and the other roller means being disposed to counteract the thrust imposed upon said rim by the aforesaid one roller means.

2. A strand processing machine comprising a driven axle mounted tractor reel including a cylindrical rim adapted to have a group of strand coils trained thereon, cutting tool means arranged to superficially treat a reel oncoming strand portion as a work piece, separate stator means respectively located alongside each rim end, stepoff ledge means for the rim interposed between said stator means, thrust imparting means carried by one such stator means serving to automatically shift the last laid rim coil axially of the reel over said stepoff ledge means when the reel is rotated, and roller means for the other stator means disposed to substantially counteract the thrust exerted by the aforesaid imparting means.

3. A strand processing machine comprising a driven tractor reel including a cylindrical rim adapted to have a group of strand coils trained thereon in single layer formation, cutting tool means arranged to superficially treat a reel oncoming strand portion as a workpiece, a coni-

cally flared enlargement for the rim region lying laterally remote from such oncoming strand portion, and roller equipped stator means whose rollers engage and direct the offcoming strand portion upwardly along said flared enlargement.

4. A strand processing machine comprising a unidirectionally driven axle mounted tractor reel including a cylindrical rim adapted to have strand coils trained thereon, cutting tool means arranged to superficially treat a reel oncoming strand portion as a work piece, ringshaped stator means located alongside one reel end, said means being provided with a series of outturned pads distributed angularly about said stator means and the face of which pads lie in substantial projected registry with the reel exterior, a bracket demountably superimposed on each such pad and provided with a guide pin directed perpendicularly with respect to the reel axis, and automatic roller means carried upon each such pin to partially overlie the rim perimeter, said roller series being collectively stepped from each other spirally inward from said one rim end to an extent greater than the treated strand gauge and serving to impart a maintained substantially uniform lateral shift movement throughout the length of the last laid coil when the reel is rotated.

5. A strand processing machine comprising a driven axle mounting a tractor reel including a cylindrical rim adapted to have strand coils trained thereon, cutting tool means arranged to superficially treat a reel oncoming strand portion as a work piece, primary two-speed motor means having a gear reduced outlet shaft directly coupled to the reel axle to run at normal speed and further having a gear carried at an armature shaft end, a supplement motor having a pinion affixed to its armature shaft, and means for selectively shifting said pinion into and out of mesh with the gear carried on the armature shaft end of the primary motor.

6. A strand processing machine comprising a unidirectionally driven axle mounted tractor reel including a cylindrical rim adapted to have strand coils trained thereon, cutting tool means arranged to superficially treat a reel oncoming strand portion as a work piece, ringshaped stator means located alongside one reel end, a T-slot extending axially of the rim exterior and the mouth of which slot is bridged by certain of the laid coils, a T-head bolt cooperating with said slot and serving to temporarily clamp a particular coil toward said rim, and automatic thrust imposing means sustained by said stator means to laterally shift the first laid coil axially of the reel.

7. A strand processing machine comprising a unidirectionally driven axle having a tractor reel mounted thereon and which reel is built up as a cylindrical sleeve-like rim section having bored end regions adapted to have strand coils laid thereon in combination with a pair of interspaced pulleys that affixedly circumscribe the reel axle and are respectively centered in the rim section bores, cutting tool means arranged to superficially treat a reel oncoming strand portion as a workpiece, and dual stator means respectively located alongside the opposed reel ends and which means are respectively equipped with thrust roller means sustained by and reversely assembled upon each such dual stator means, one of the roller means serving by its thrust to laterally skid the last laid coil axially of said reel and the other roller means being disposed to counteract the skid thrust im-

parted upon said rim by the aforesaid one roller means.

8. A strand processing machine comprising a driven axle mounting a tractor reel thereon of which the rim perimeter is shaped to provide for a pair of cylindrical steps of different diametral size adapted to have strand coils laid therealong, cutting tool means arranged to superficially treat a reel oncoming strand portion as a work piece, means shifting said laid coils laterally, and a sheath possessing an inherently low friction coefficient disposed to embrace the smaller of said step diameters to facilitate coil slip therealong.

9. A strand processing machine comprising a tractor reel adapted to have strand coils trained thereon, grinder head means arranged with a roll of abrasive tape that superficially treats a reel oncoming strand portion as a workpiece, said means including a disc wall carrying a gear mounting pin, a feed roller having a driven shank rotatably extending through said wall, a compensating gear affixed about the axis of the roller shank and interposed between said wall and the feed roller, and a mated idler gear mounted upon said wall pin in mesh with the compensating gear.

10. A strand processing machine comprising a tractor reel adapted to have strand coils trained thereon, grinder head means arranged with a roll of abrasive tape that superficially treats a reel oncoming strand portion as a workpiece, said means including a disc wall, a feed roller having a driven shank rotatably extending through said wall and the surface of which roller is conically shaped to drag abrasive tape toward such conical roller surface in a maintained substantially perpendicular relation to the feed roller axis.

11. A strand processing machine comprising a tractor reel adapted to have strand coils trained thereon, grinder head means arranged with a roll of abrasive tape that superficially treats a reel oncoming strand portion as a workpiece, said means including a disc wall having a centralized grinder zone, a pair of interspaced mounting pins carried within a semicircular face region of said disc wall, a supply bobbin having roll tape thereon and a tape offtake bobbin respectively mounted on said pins and which bobbins are conjoined by a continuous tape portion with the grit exposed radially outward on each such bobbin, an idler roller diverting said continuous tape portion through the grinder zone, a tape backing shoe operatively impressing the grit thereof toward such zone, and driven feed roller means interposed between said zone and the offtake bobbin to draggily withdraw tape from its supply bobbin onto the takeoff bobbin, said feed roller being equipped with compensating means to automatically abate tape slackness between said feed roller and its offtake bobbin.

12. A strand processing machine comprising a tractor reel adapted to have strand coils trained thereon, grinder head means arranged to superficially treat a reel oncoming strand portion with abrasive roll tape as a dragged workpiece, said means including a disc wall having a centralized abrasive tape grinder zone, a tape supply bobbin and a pin mounted tape offtake bobbin carried by said wall and which bobbins are interconnected by a tape portion that is dragged through said zone, the hub of said offtake bobbin being sectionalized to comprise a pair of relatively shiftable conical tube elements that are telescopically disposed, a driven feed roller serving to transferably advance said interconnecting tape portion

5 off the supply bobbin, and compensating gear means operatively interposed between the feed roller and the inner conical tube element of the offtake bobbin to keep taut the advancing tape after it leaves its feed roller.

13. A strand processing machine comprising a tractor reel adapted to have strand coils trained thereon, grinder head means arranged to superficially treat a reel oncoming strand portion with abrasive roll tape as a dragged workpiece, said means including a disc wall having a centralized abrasive tape grinder zone, a tape supply bobbin and a pin mounted tape offtake bobbin carried by said wall and which bobbins are interconnected by a tape portion that is dragged through said zone, the pin of the offtake bobbin being adjustably tiltable with respect to the disc wall, a driven feed roller serving to transferably advance said interconnecting tape portion off the supply bobbin, and retaining means setting said pin into a fixed tilt position.

14. A strand processing machine comprising a tractor reel adapted to have strand coils trained thereon, tubular head means affording an abrasive tape grinder zone kept in operative contact with a reel oncoming strand portion as a dragged work piece, an elongated pivotally mounted shoe imposing a grit backing thrust upon the tape, and a longitudinal slot registering with the tape 30 contacting face of said shoe and having a cushioning strip inset therein.

15. A strand processing machine comprising a tractor reel adapted to have strand coils trained thereon, tubular head means affording an abrasive tape grinder zone kept in operative contact with a reel oncoming strand portion as a dragged work piece, an elongated pivotally mounted shoe imposing a grit backing thrust upon the tape, the tape contacting face of said shoe having a substantially rectangular slot sunk therealong, and a partially receding cushioning strip inserted in said slot to leave a cavity therebetween.

16. A strand processing machine comprising a tractor reel adapted to have strand coils trained thereon, tubular head means affording an abrasive tape grinder zone kept in operative contact with a reel oncoming strand portion as a dragged work piece, and an elongated pivotally mounted shoe imposing a grit backing thrust upon the tape, the tape contacting shoe face being slotted lengthwise and having a cushioning strip inserted therein that provides for a shoe face protuberance extending outwardly beyond the cross-sectional confines of said cushioning strip.

17. A strand processing machine comprising a tractor reel adapted to have strand coils trained thereon, tubular head means affording an abrasive tape grinder zone kept in operative contact with a reel oncoming strand portion as a dragged work piece, and an elongated pivotally mounted shoe imposing a grit backing thrust upon the tape and providing for side face lug means together with a shoe inserted cushioning strip mounted to straddle the tape contacting region of said backing thrust and which lug means mounts a tape guiding roller thereon.

18. A strand grinding machine comprising a tractor reel adapted to have strand coils trained thereon, chambered head means including a rim flange encircling a pair of opposed abrasive tapes that operatively contact an interposed reel-oncoming strand portion as a laterally shiftable work piece, a pair of trunnion mounted shoes that respectively impose a grit backing thrust upon

each of the opposed abrasive tapes, and rod means radially through the rim flange to adjustably position one of the shoe trunnions and thereby centralize laterally shiftable work piece with respect to the rim flange.

19. A strand grinding machine comprising a tractor reel adapted to have strand coils trained thereon, chambered head means including a rim flange encasing a pair of opposed abrasive tapes that operatively contact an interposed reel-oncoming strand portion as a laterally shiftable workpiece, a pair of trunnion mounted shoes that respectively impose a grit backing thrust upon each of the opposed abrasive tapes, adjustable rod means extending radially through the rim flange and serving to fix a shoe trunnion position, and adjustable resilient means counterthrusting the other shoe trunnion toward such adjustably fixed trunnion position.

20. A strand grinding machine comprising a tractor reel adapted to have strand coils trained thereon, chambered head means including a rim flange having an open mouth arranged to embrace a pair of opposed abrasive tapes that operatively contact an interposed reel oncoming portion as a workpiece, panel means demountably covering said mouth, a pair of relatively movable tape backing shoes that thrust each such tape toward its respective grinder zone, and adjusting means extending through the rim flange for independently shifting either shoe position while said mouth remains covered.

21. A strand processing machine comprising a tractor reel adapted to have strand coils trained thereon, a superstructure including a pair of laterally spaced stringer beams extending perpendicularly to the reel axis, a tubular spindle interposed between said beams and having a grinder head carried at one spindle end to treat a reel oncoming strand portion disposed in loop formation as an endless workpiece batch, an idler sheave serving to divert such loop through the spindle, and a bundling drum having a motor driven shaft that axially lies athwart one such beam and is supported thereby.

22. A strand processing machine comprising a tractor reel adapted to have strand coils trained thereon, a superstructure including a pair of laterally spaced stringer beams extending perpendicularly to the reel axis, a tubular spindle interposed between said beams and having a grinder head carried at one spindle end to treat a reel oncoming strand portion disposed in loop formation as an endless workpiece batch, an idler sheave serving to divert such loop for entrance through the spindle, a batch replenishing drum together with a motorized bundling drum carried at the end region of one such beam in interposed relation to the sheave and adjacent grinder head, said bundling drum being smaller in diametral size than the sheave, and a precrimping device located between the bundling drum and said sheave.

23. A processing machine for treating successive strand batches of different lengths and which machine comprises a driven tractor reel including a rim adapted to have a series of wrapped strand coils spirally trained thereon with the opposed strand ends originally spliced into continuous loop formation, cutting tool means arranged to perimetricaly treat a reel oncoming strand portion of said loop as a workpiece, stator means located adjacent one end of said rim and having a stator sustained roller that shifts said wrapped coils laterally in a direction lengthwise

5 of the reel axis, a supply drum carrying a replenishment batch thereon, a batch offtake drum provided with controllable drive means and disposed to stow a completed batch thereon upon severing said original loop splice, and means for selectively incorporating or eliminating surplus run coils between the severed ends of such successive batches and thereupon splicing the remaining coils into renewed loop formation.

10 24. A strand grinder comprising in combination an axle driven horizontal tractor reel including a rim adapted to have a group of strand coils spirally trained thereon, cutting tool means arranged to superficially treat a reel oncoming strand portion as a workpiece, dual stator means encircling the reel axle and respectively located contiguous to each rim end, said dual stator means being interbraced by multiple stay rods mounted to constitute a rockable cradle, and plural angularly distributed thrust roller means each independently sustained by a demountable bracket and reversely assembled upon each of the dual stator means, one of such roller means serving to laterally skid the last laid rim coil axially 15 of said reel and the other roller means being disposed to counteract the thrust imposed upon said rim by the aforesaid one roller means and which cradle when rocked carries a certain lower bracket into a relatively raised position to facilitate unobstructed access thereto.

20 25. A strand grinder unit comprising a driven tractor reel adapted to have strand coils trained thereon as a dragged workpiece component, tubular head means having a reel oncoming workpiece portion entered therethrough, abrasive tape fed into cutting engagement with such workpiece portion to constitute a grinder zone, said head means being equipped with a rotatable supply bobbin carrying a roll of tape thereon that is tape 25 interconnected to a corresponding offtake bobbin and which bobbins are rendered interchangeable, and tape feed means driven in unison with said reel and serving during an initial tape pass to transfer roll tape from said supply bobbin to its corresponding offtake bobbin as delivered in a partially expended grit condition and which bobbins are simultaneously rotated by the tape feed means in one and the same direction with the tape grit faced radially outward relative to their respective bobbin axes, such supply and offtake bobbins after being interchanged serving to further deplete the tape grit by a reversed pass through its grinder zone.

30 26. The method of processing a strand that is reel dragged linearly at a relatively fast travel rate and which method consists in bringing said strand into crosswise superficial cutting zone engagement with an abrasive tape initially having an original grit face of finite length of which the 35 end regions are respectively wound to form complementary roll components whose grit is laid to leave a transferable medial tape region that subtends such rolls, said rolls as a first step being simultaneously rotated at a relatively slow tape transfer rate to partially expend said original tape grit, and then as a subsequent step further utilizing such partially expended grit in a reversed pass direction through said zone.

40 27. The method of processing a metallic strand that is dragged by a driven reel and linearly advanced at a relatively rapid travel rate and which method consists in bringing a reel oncoming portion of said strand into crosswise superficial cutting zone engagement with an abrasive tape initially having a virgin grit face of which the

end regions are respectively roll wound into identical spiral formations with the tape grit laid outwardly and which rolls are respectively carried interchangeably upon a supply bobbin and an offtake bobbin actuated by a driven feed roller to leave a subtending medial active tape region that is transferably passed between said bobbins at a relatively slow feed rate whereby as an initial step to partially expend in one pass direction said virgin tape grit throughout the major portion of its length and then as a subsequent step further utilizing such partially spent grit in a reversed pass direction by bobbin interchange, the prevalent offtake bobbin being actuated by a maintained unidirectional roller rotation irrespective of the tape pass direction.

28. A strand grinder machine comprising in combination a driven reel adapted to drag a batch of endless strand directed to travel in a closed circuit as a workpiece, grinder head means including an apertured web member having a reel oncoming strand component entered therethrough a pair of driven duplex feed rollers operated in unison with said reel and which rollers are located in substantial straddling alignment to the web aperture, a tape supply bobbin and a complementary offtake bobbin assembled to each side of said feed rollers in a common face of the web member, a separate abrasive tape having its end regions wound about such set of bobbins and which tapes respectively provide for a spanning medial tape region extended into operative cutting zone engagement with opposed sides of said workpiece, and diametrically interspaced tape guide rollers whose centers are divergently inclined with respect to a corresponding feed roller to form an angle therebetween of which the reversed apexes respectively lie closely contiguous to such double acting cutting zone and which angular divergence widens in either direction as measured outwardly away from said zone.

29. A strand grinder machine comprising in combination a driven reel adapted to drag a batch of endless strand directed to travel in a closed circuit as a workpiece, grinder head means including an apertured disc member having a reel oncoming strand component centrally entered therethrough, a feed roller driven in unison with said reel and located within the confines of a semicircular disc face in a contiguous relation to one of the cusp regions thereof, a tape supply bobbin and a similar offtake bobbin respectively mounted in a radially offset relation to the disc aperture and in an interposed relation to both cusps of said confines, a common abrasive tape having its end regions wound respectively upon such bobbins with a spanning medial tape region extended into cutting engagement with the workpiece, and a reversing gear interposed between the offtake bobbin and its driven feed roller to rotate the last named bobbin in the same direction as the supply bobbin.

30. A strand grinder machine comprising in combination a unidirectionally driven tractor reel having a cylindrical rim adapted to drag a batch of endless strand redirected by guide means to travel in a closed circuit as a workpiece and of which a strand component is laid upon said rim to form a group of prewrapped coils, and stator means located adjacent to one reel and provided with camming means including an automatically retractible roller of which one end face is mounted to resiliently lift away from a close running reel rim, the perimeter of said roller being

applied in aligned registry with a prewrapped coil to laterally skid the last named coil toward the other reel end.

31. A processing machine for successively treating strand batches of different lengths and which machine comprises a driven tractor reel including a cylindrical rim element provided with an axially directed T-slot sunk in the perimeter thereof and which rim element is adapted to have a series of wrapped strand coils spirally trained thereon crosswise over said slot, a grinder head having a reel oncoming strand portion brought into operative engagement therewith, a headed bolt interlockingly enterable into the rim slot serving to demountably clamp a particular wrapped strand coil to the rim and permitting an adjacent coil of a previously installed batch to be raised radially from its rim to facilitate severing the last named coil.

32. The method of abrasively processing in stepwise multistages, an endless metallic strand that is repeatedly laid upon a driven reel in successive passes for recurrent coil stowage thereon, and which method consists in bringing a reel oncoming strand portion into maintained tangential cutting zone engagement with an abrasive tape initially having a substantially virgin grit face of finite length of which the end regions are respectively wound in roll formation and interchangeably mounted upon a supply and an actuated offtake bobbin to leave a subtended active tape region that is reciprocatively transferred between said bobbins at a feed rate materially slower than the linear rate imparted to the strand whereby as an initial step, to partially expend such virgin tape grit throughout the major portion of its length, and then as a further step, utilizing such partially spent tape grit in a linearly reversed grinder stage while said stowed coils remain installed about the reel until the available remaining tape grit becomes more completely spent.

33. The method of abrasively expediting in multistages, a relatively large gauged endless wire-making rod batch affording a comparatively small superficial area per foot of length, said looped rod being redirected by guide sheave means into a closed circuitous travel path of which a major length component is recurrently laid during each revolution upon a unidirectionally driven tractor reel in bundled stowage fashion and which method consists in uninterruptedly bringing a reel oncoming rod constituent into crosswise cutting zone engagement with a rotatably mounted abrasive tape providing for coarse-grit substantially virgin grit that it rotated about the entire perimeter of said constituent while simultaneously feeding such grit linearly toward said zone in unison with the reel rotation whereby as an initial step to partially deplete such grit and incompletely reduce the original rod gauge by a prescribed comparatively small degree, and then by a supplementary grinder step grinding the aforesaid initial rod batch to a smaller gauge size by further utilizing said partially depleted tape grit without dismantling the stowed bundle off its reel and while the rod gauge reduction remains closely confined to said original size without involving a significant combined enlargement of its initial superficial area per foot of length.

34. The method of abrasively processing in stepwise multistages, a wire-making hot rolled rod batch of stock having finite ends abuttingly conjoined into an endless workpiece and which looped rod stock is linearly dragged and redirected

21

by sheave means into a closed circuitous travel path of which a component is initially installed and laid upon a cylindrically smooth unidirectionally driven tractor reel in layer formation that is laterally shiftable bodily in the direction of the reel axis and which method consists in bringing a reel oncoming rod constituent into crosswise cutting zone engagement with an abrasive tape providing a substantially virgin grit face that is rotated around the perimeter of said constituent while simultaneously feeding the engaged tape face linearly toward said zone whereby to partially complete the grinding therein and incompletely reduce the original rod gauge, and then by augmented utilization of such partially depleted grit as applied in a next succeeding stage to the same previously installed endless batch until the tape grit becomes substantially depleted, thereby further reducing the diametral sizing of said batch throughout its entire length without material rod stock end wastage, the jointed workpiece loop end regions being thereupon severed and the ground rod stock cold drawn into a smaller wire gauge.

35. The method of utilizing abrasive tape grit in multistages as applied to an endless wire-making rod batch of comparatively heavy gauge and which looped rod is dragged along a circuitous travel path of which a component is recurrently trained in layer formation upon a unidirectionally driven reel in a certain direction of workpiece traverse, and which method as one of its stages consists in bringing a reel oncoming rod constituent into crosswise cutting zone engagement with an abrasive tape that is linearly advanced about the perimeter of said constituent to selectively feed grit through said zone in one pass direction, and which same tape in a subsequent stage is fed in a linearly reversed pass direction while said unidirectional rod stock traverse remains unchanged.

36. The method for abrasively processing a series of strand batches of diverse finite lengths in stepwise succession in which the respective mated ends of each such batch are conjoined to constitute a separate endless workpiece arranged to be guided into a closed circuitous travel path of which a component is individually installed and recurrently laid upon a unidirectionally driven tractor reel and which method consists in placing a particular reel oncoming batch constituent into crosswise cutting engagement with an abrasive tape agency until the diametral sizing given to said particular batch has been completed, then

22

severing such finished endless batch in the conjoined region thereof and introduce therebetween a next succeeding batch whereby to linearly drag said preceding batch onto a driven takeoff drum having its original batch length restored without involving substantial strand wastage.

37. A strand grinder machine comprising a cylindrically plain tractor reel mounted upon a driven axle and adapted to have laterally shiftable strand coils laid upon the reel perimeter as a workpiece initially having finite ends that are abuttingly conjoined into a looped endless batch that is guided along a closed circuitous travel path by an axle mounted skew sheave, grinder head means placed into operative cutting engagement with a reel oncoming strand portion, stator means located alongside one reel end and serving to laterally shift said coils toward the other reel end and which loop engaged skew sheave brings the reel offcoming strand portion into realignment with the grinder head means, and jack means adjustably imposing a coil tensioning effort upon the skew sheave.

38. A strand processing machine comprising a driven tractor reel including a rim adapted to have a group of laterally shiftable coils trained thereon as an endless workpiece, grinder head means arranged to superficially abrade a reel oncoming strand portion, said head means including a driven tubular spindle mounting a chambered head having an open mouth with the workpiece threaded therethrough, said mouth being closable by a segmentally split transparent panel having the strand slidably entered therebetween, and reversely mounted strand shift roller means sustained in fixed interspaced relation to the respective reel ends, one of such roller means serving to laterally shift the last laid coil axially of said reel and the other roller means being disposed to counteract the thrust imparted upon said rim by the aforesaid one roller means.
